CLAIM

The ornamental design for a wearable finger ring device, as shown and described.

DESCRIPTION

FIG. 1 is a perspective view of a wearable finger ring device showing our new design;

FIG. 2 is a front elevational view thereof;

FIG. 3 is a rear elevational view thereof, the left side elevational view and right side elevational views being identical thereto;

FIG. 4 is a top plan view thereof, the bottom plan view being identical thereto; and,

FIG. 5 is a cross-sectional view taken along line 5-5 of FIG. 2.

The broken lines illustrate portions of the wearable finger ring device which form no part of the claimed design.
